ICE MAKING MACHINE

William H. Taylor, Muskego, Wis., assignor, by
means assignments, to Reconstruction Finance
Corporation, Chicago, Ill., a corporation

Application January 17, 1935, Serial No. 2,230

12 Claims. (Cl. 62—105)

The present invention relates in general to improvements in the art of manufacturing ice, and relates more specifically to improvements in the construction and operation of machines for making so-called slush or snow ice.

Generally defined, an object of the invention is to provide an improved ice making machine which is simple and compact in construction, and which is also highly efficient in operation.

It has heretofore been proposed to cool and harden liquid by permitting the same to flow along the internal surface of a cylinder surrounded by a cooling jacket, and to remove the cooled or frozen liquid from the cooling surface with the aid of a revolving scraper, the cylinder being vertically disposed and having an open lower end so that the final product could be delivered therefrom by gravity. In these prior liquid congealing machines, it was necessary to make the cylinder of considerable length in order to secure commercial capacity; and by virtue of the fact that the scraper coated with the cooling surface throughout the entire length of the latter, excessive power was required in order to move the scraper therealong. The prior machines would also tend to stall due to undesirable accumulations of ice therein and were, moreover, relatively ineffective due to inefficient application of the liquid and refrigerant to the cooling zone; and these deficiencies, combined with other complications in structure, have made the prior freezers of this type relatively impractical.

It is therefore an object of the present invention to provide an improved liquid congealing machine of the above-described general type, which overcomes all of the defects mentioned, and which is thoroughly practical in actual use.

Another specific object of the invention is to provide an improved rotor structure for rapidly and effectively removing successive films of ice from a freezing surface.

A further specific object of the invention is to provide an improved liquid congealing or freezing chamber whereby a maximum quantity of liquid may be converted into ice with the aid of a minimum quantity of refrigerant.

Still another specific object of the invention is to provide improved structure for preventing undesirable accumulation of ice within a liquid cooling and hardening assemblage, thereby making it possible to maintain such systems or machines in continuous operation.

An additional specific object of the invention is to provide improved liquid distributing systems for pre-cooling the liquid and for more effectively delivering the same to the freezing surface.

Another specific object of the invention is to provide various improvements in the details of

construction of automatic ice making machines, whereby the costs of construction and operation thereof are reduced to a minimum, while the efficiency is enhanced to a maximum.

These and other objects and advantages will be apparent from the following detailed description.

A clear conception of an embodiment of the invention and of the mode of constructing and of utilizing ice making machines and systems built in accordance with the improvement may be had by referring to the drawings accompanying and forming a part of this specification, in which like reference characters designate the same or similar parts in the various views.

Fig. 1 is a central vertical section through one of the improved ice making machines fully assembled;

Fig. 2 is a transverse horizontal section through the ice making machine of Fig. 1, taken along the line 2—2;

Fig. 3 is a diagram of a system in which the improved ice making machine may be used to advantage;

Fig. 4 is a bottom view of the lower ice discharge and liquid pre-cooling ring of the machine;

Fig. 5 is a full top view of the scraper-carrying rotor; and

Fig. 6 is a side elevation of the rotor of Fig. 5.

While the invention has been shown and described herein as being applied to a relatively small unit and system for converting water into slush or snow ice, it is not intended to unnecessarily restrict the scope by such specific embodiment since some of the novel features may obviously be applied to other types of machines used for other cooling purposes.

Referring to the drawings, the improved ice making system shown diagrammatically in Fig. 3 comprises in general the ice making unit 8; an ice receiving screen 9 disposed beneath the open lower end of the unit 8 and from which the deposited slush or snow ice may be constantly removed by a suitable conveyor; a water receptacle 10 disposed beneath the screen 9 for catching the excess liquid removed from the ice by the screen; a fresh water supply pipe 11 leading to the lower ring of the unit 8 and having therein a control valve 12 which is controlled by a float 13 resting on the liquid within the receptacle 10; a liquid discharge pipe 14 leading from the lower ring of the unit 8 to the lower portion of the receptacle 10; and a liquid supply pump 15 for the unit 8 having a suction pipe 16 communicating with the receptacle 10 in line with the discharge end of the pipe 14 and also having a liquid delivery pipe 16 communicating with the unit 8.

The improved ice making unit 8 shown as-

sembled in Figs. 1 and 2 consists primarily of an evaporator coil preferably comprising a circular casing 17 formed of a single, helically-wound length of square-sectioned tubing having a substantially cylindrical, inner ice-forming surface 18; a rotor 19 mounted upon a central vertical shaft 20 within the casing 17 and having three radial arms 21 carrying relatively staggered scrapers 22 which are cooperable with the surface 18; and an electric motor 23 drivingly connected to the upper end of the shaft 20 for propelling the rotor 19.

The tubular casing 17 may be formed of suitable metal, such as aluminum, and has a lower liquid refrigerant inlet 25 and an upper gas outlet 24 associated with the opposite ends thereof, and this casing 17 may be surrounded by an insulating outer casing 26 formed of concentric shells separated by an intervening layer of insulation 27. The lower ice discharge and liquid pre-cooling ring 28 with which the water pipes 11, 14 communicate as shown in Figs. 1 and 4, is secured to the lower end of the casing 26 beyond the bottom of the casing 17; and a lower spider 29 is secured to and forms a closure for the passage 30 within the ring 28 and also supports a lower anti-friction bearing 31 within which the lower end of the rotor-supporting shaft 20 is journaled. The upper end of the outer casing 26 supports an upper spider 32, the central portion of which carries an upper anti-friction bearing 33 coacting with the upper portion of the shaft 20, so that this shaft is effectively supported for free rotation centrally within the circular casing 17.

The spacer-carrying rotor 19 is drivingly connected to the main shaft 20 by means of keys 34 and set screws coacting therewith, and has an integral central liquid receptacle 35 of relatively large capacity from which the arms 21 radiate (see Figs. 1, 2, 5, and 6). The lower portion of the rotor 19 is also provided with an integral cap 36 for protecting the lower bearing 31, and the liquid delivery pipe 16 of the pump 15 communicates with a passage 37 in the central portion of the upper spider 32 so that the pre-cooled fresh water will be deposited directly into the upper end of the receptacle 35 at all times. The lower extremity of the receptacle 35 may be provided with a drain plug 38, and a series of liquid distributing pipes 39 having discharge openings 40 as shown in Fig. 6, directed toward the freezing surface 18, are carried by the rotor 19 and communicate with the upper portion of the receptacle 35. It will be noted that one of the distributing pipes 39 is located closely adjacent to the outer rear extremity of each of the arms 21 of the rotor 19, and that the depending perforated portions of these pipes extend parallel to and throughout the entire length of the freezing surface 18 and have sealed lower ends. As shown, there are two scrapers 22 detachably secured to each arm 21 by means of cap screws 41; and as previously stated, the scrapers 22 are staggered, as clearly shown in Fig. 6, so as to cover the entire freezing surface 18 during each complete revolution of the rotor 19. The attaching screws 41 preferably permit slight adjustment of the scrapers 22 toward and away from the surface 18, and the cutting edges of these scrapers may be serrated if so desired.

The electric motor 23 may be connected to a counter-shaft 42 by means of worm gearing confined within a supporting casing 43 carried by the upper spider 32, and the lower end of the

shaft 42 is drivingly connected to the upper end of the rotor-supporting shaft 20 by a flexible coupling 44 which is effectively protected by the casing 43 and spider 32 as shown in Fig. 1. It will be noted that by disconnecting the water supply pipe 16 and the fastening between the spider 32 and the outer casing 26, the entire rotor structure may be freely removed as a unit from within the casing 17; and by disconnecting the fastening between the casing 43 and the upper spider 32, the driving motor 23 and counter-shaft 42 may be removed without disturbing the rotor 19 and other parts of the unit.

During normal operation of the improved ice making machine, the inlet valve 12 is open to admit fresh liquid through the pipe 11 to the passage 30 and from the passage 30 through the pipe 14 to the receptacle 10. The rotor 19 is being operated by the electric motor 23 to cause the scrapers 22 to advance along the freezing surface 18 and to remove the ice film formed by the refrigerant within the casing 17, from this surface. This ice is delivered, in the form of snow or slush mixed with a slight excess of water, by gravity, directly upon the screen 9; and the excess water is quickly drained therefrom into the receptacle 10. The pump 15 is operating and withdrawing liquid from the receptacle 10 through the suction connection 16' and is delivering this liquid in pre-cooled condition through the pipe 16 and passage 37 into the receptacle 35 of the rotor 19. The pre-cooling of the liquid thus admitted is effected both during the flow of the fresh liquid through the passage 30 and due to the contact of the drainage liquid delivered to the receptacle 10 through the screen 9, with the ice particles; and the fresh liquid delivered from the pipe 16 into the lower end of the pump suction pipe 16' prevents ice particles from accumulating at the lower end of the pipe 16' and thereby interrupting the supply of liquid to the pump. Liquid from within the rotor receptacle 35 is delivered by centrifugal force and hydrostatic head, into distributing pipes 39 and is being constantly delivered through the openings 40 in these pipes, to the cylindrical freezing surface 18 where fresh films of ice are formed as rapidly as the scrapers 22 remove the film therefrom. In this manner, successive films of ice are removed from the surface 18 and are deposited in the form of snow ice upon the screen 9 from whence the dry snow may be removed with a suitable conveyor in an obvious manner.

During such normal operation of the machine, the refrigerant which is admitted to the casing 17 through the inlet 25, in liquid form, is converted into gas as the cooling action takes place; and the resultant gaseous refrigerant is ultimately delivered from the outlet 24. The insulating jacket provided by the outer casing 26 and insulation 27 prevents undesirable heating of the casing 17 from the exterior of the unit, and the helical formation of the passage within the casing 17 will insure most effective absorption of the heat from the water delivered upon the surface 18. The staggered formation or disposition of the scrapers 22 permits a suitable film to congeal upon the freezing surface 18 during each revolution of each of the individual scrapers, while still enabling the use of a multiplicity of scrapers to thereby increase the capacity of the machine to a maximum. The relatively large body of liquid within the receptacle 35 prevents the rotor arms 21 from becoming excessively cooled, and there-

by prevents accumulation of ice upon the rotor, in spite of the fact that the liquid within the receptacle 35 has been pre-cooled. The liquid flowing through the passage 30 likewise retains the lower portion of the machine at such temperatures that the ice will not accumulate thereon, thus insuring proper functioning of the unit without hindrance by ice accumulations.

The bearings 31, 32 are effectively protected against entry of foreign matter, and the entire machine may be readily dismantled by merely releasing the spiders 29, 32 and subsequently removing the remaining structural elements. The machine may be just as readily assembled, and when it has been properly assembled, provides an extremely compact unit having relatively large capacity considering the space occupied thereby. The improved machine has proved highly successful in actual use and may be manufactured 20 and operated at relatively low cost.

It should be understood that it is not desired to limit the invention to the exact details of construction and to the precise mode of operation herein shown and described, for various modifications within the scope of the claims may occur 25 to persons skilled in the art.

It is claimed and desired to secure by Letters Patent:

1. In combination, a casing comprising a single helical tube of polygonal cross-section successive sections of which coact to provide a continuous circular freezing surface, means for introducing refrigerant into said casing to cool said surface, means for delivering liquid to said surface, and 30 a scraper for removing congealed liquid from said surface.

2. In combination, a casing comprising a single helical tube of rectangular cross-section successive sections of which coact to provide a continuous cylindrical inner freezing surface, means for introducing refrigerant into said casing to cool said surface, means for delivering liquid to said surface, and a movable scraper for removing congealed liquid from said surface.

45 3. In combination, a casing comprising a continuous helical tube successive sections of which coact to provide a continuous circular freezing surface having straight line generatrices about a vertical axis, means for admitting refrigerant to the interior of said casing, means for delivering liquid to said surface, and a rotor revolvable about said axis to remove congealed liquid from said surface.

4. In combination, a casing having an annular 55 cooling surface generated about a vertical axis, a rotor having cutters cooperable with said surface to remove ice therefrom, a hollow heat transfer member having an annular internal passage enclosed by an annular wall disposed near the lower end of said surface, and means for delivering liquid to said surface through said passage.

5. In combination, a vertical annular casing having a refrigerant chamber therein and having an internal cooling surface, means forming an annular heat transfer passage near the lower end of said surface, a rotor revolvable within said casing and having ice removing elements movable along said surface, and means for conducting liquid through said passage and for subsequently delivering said liquid in precooled condition to said surface.

6. In combination, a casing having an annular internal freezing surface and an open lower end, a spider disposed adjacent said lower casing end, a shaft disposed centrally within said casing and having a bearing disposed within a recess in said spider, a rotor carried by said shaft and having an integral protecting cap covering said recess and projecting downwardly to completely conceal said bearing, and ice removing means carried by said rotor and cooperating with said surface.

7. In combination, an evaporator coil comprising a continuous helical tube having a flat side providing a continuous annular internal surface having a vertical axis, means for delivering liquid to said surface, and a scraper for removing congealed liquid from said surface.

8. In combination, an evaporator coil comprising a single helical tube having a flat side providing a continuous annular internal surface having a vertical axis, means for admitting refrigerant to the lower portion of said coil, means for delivering liquid to said surface, and a scraper for removing congealed liquid from said surface.

9. In combination, a casing having an annular vertical internal freezing surface and an open lower end, a rotor revolvable within said casing and having a central upwardly open liquid receptacle and a series of solid fin-like heat conducting arms radiating from said receptacle, said receptacle having a relatively deep liquid receiving space therein and said arms extending inwardly in close proximity to said space throughout the entire height thereof, ice removers carried by the outer ends of said arms and cooperating with said surface, and liquid conducting pipes extending outwardly from the upper portion only of said receptacle and downwardly along said surface rearwardly of said arms.

10. In combination, an annular casing having an internal freezing surface and an open lower end, a rotor revolvable within said casing, said rotor comprising a central deep liquid receptacle and solid fin-like arms of considerable vertical width radiating from said receptacle, scrapers carried by the outer ends of said arms and cooperating with said surface, and liquid conducting pipes extending laterally from said receptacle and downwardly along said surface rearwardly of said arms.

11. In combination, a casing having an internal annular freezing surface free from irregularities throughout its length, a rotor having arms extending toward said surface, and a scraper carried by each of said arms and coacting with said surface, each scraper having a path of action overlapping the path of coaction of another of said scrapers with said surface.

12. In combination, a casing having an internal cylindrical freezing surface generated about an upright axis and free from irregularities throughout its length, a rotor having arms extending toward said surface, and vertically spaced scrapers carried by each of said arms and coacting with said surface, said scraper having a path of action overlapping the path of coaction of another of said scrapers with said surface.
